Patented June 9, 1914.

UNITED STATES PATENT OFFICE.

MARK KNOX MARLOW, OF BLOCK, TENNESSEE.

AUTOMATIC RAILWAY-SWITCH.

1,099,807.

Specification of Letters Patent.

Patented June 9, 1914.

Application filed September 19, 1913. Serial No. 790,753.

To all whom it may concern:

Be it known that I, MARK KNOX MARLOW, a citizen of the United States, residing at Block, in the county of Campbell and State 5 of Tennessee, have invented new and useful Improvements in Automatic Railway-Switches, of which the following is a specification.

This invention is an improved automatic 10 railway switch which is adapted to be actuated by the train wheels to set the switch rail as the train enters the main track from a side or switch track and thus avoid all dangers resulting from misplaced switch rails, 15 the invention consisting in the construction, combination and arrangement of devices hereinafter described and claimed.

In the accompanying drawings: Figure 1 20 is a plan of an automatic railway switch constructed in accordance with my invention. Figs. 2 and 3 are vertical transverse sectional views of the same on the planes indicated by the lines *a—a* and *b—b*, respectively.

The main track rails are indicated at 1, 25 the side rails at 2 and the switch rails at 3. The inner side rails converge to a point or frog 4. The outer side rails are shown as integral with and bent from the main rail as at 5. The switch rails are secured at 30 their converging ends 6 near the frog 4 and their opposite ends are free to move toward and from the main rails and are arranged on the inner sides of the main rails. The switch rails 3 are of the type known as split rails, 35 each tapering to a point at its free end as at 7. The free ends of the switch rails are arranged to move on a tie 8 and are connected together by a rod 9 the ends of which are pivotally connected as at 10 to clip plates 11 40 which are bolted on the base flanges 12 of said switch rails. The rod 9 which connects the switch rails adapts them to move simultaneously in the same direction so that when one switch rail is moved and caused 45 to bear against the inner side of one of the main rails the other switch rail is moved away from the other main rail. The points of the switch rail are also pivotally connected as at 13 to a bridle rod 14. Links 15 50 are pivotally connected to the ends of the bridle rod as at 16 and the bridle rod is also provided with a locking arm 17 which extends from one end thereof and is provided with a locking lug 18 which has oppositely 55 beveled sides that converge outwardly from said arm. A locking bolt 19 is mounted for

movement in a guide frame and casing 20 which is secured on a tie 21 and a guide 22 for the outer ends of the locking arm 17 is also secured on the said tie. The locking lug 60 is movable by the operation of the bridle rod across one end of the locking bolt and the latter has a locking point 23 which is oppositely beveled and is arranged reversely with reference to the lug 18. A spring 24 is provided to project the point of the locking bolt into the path of the locking lug. Hence 65 when the switch rails are in either position one beveled side of the locking point of the bolt bears against one beveled side of the 70 locking lug and the locking bolt, by reason of the tension of its spring, holds the switch points in such position and prevents them from being casually moved.

Bed timbers 25 are arranged on the outside of the outer side rails 2 and are supported on ties 26. The upper surfaces of these bed timbers are covered with plate iron and are level with the heads of the rails. Switch operating rails 28, which are adapted 80 to be operated by the train wheels are arranged on the bed timbers and pivotally mounted at their inner ends as at 29 the outer end of the said switch operating rail being outturned as at 30. Each switch operating rail has a base flange 31 on its outer side. Said switch operating rails, being arranged on the bed timbers 25 lie in higher planes than the track rails and hence when 85 a train approaches the main track from either of the sidings or switch tracks its wheels on one side engage one of the rails 28 and moves the latter outwardly, as will be understood. Each rail 28 is pivotally connected 90 at its free end as at 32 to a lever 33. 95 Each lever 33 is fulcrumed at a point midway between its ends on the tie 8 as at 34 and its opposite end is pivotally connected as at 35 to one set of the links 15 and hence is connected to one end of the bridle rod. 100 The bridle rod and the levers 33 form connections between the switch operating rails which cause said switch operating rails to move simultaneously in reverse directions. A train when running on to the main track 105 from either side will automatically set the switch and hence all danger from misplaced switches will be avoided.

Having thus described my invention, I 110 claim:

In a railway switch in combination with main and side rails and pointed switch rails

on the inner sides of the main rails, a bridle rod connecting the free ends of the pointed switch rails, bed timbers on the outer sides of the outer side rails, train wheel operated rails on the said bed timbers and supported thereby at the outer sides of and at a higher plane than the outer side rails, the said train wheel operated rails being pivotally mounted at their inner ends and having their outer ends outturned, and levers con-

nected to the outturned outer ends of said train wheel operated rails and also connected to said bridle rod, said levers being fulcrumed at points intermediate their ends.

In testimony whereof I affix my signature ¹⁵ in presence of two witnesses.

MARK KNOX MARLOW.

Witnesses:

BEN H. SMITH,
JOHN R. IVEY.
